Inventor,
Bevill W. Whitworth, by
G. C. Kennedy,
Attorney.

UNITED STATES PATENT OFFICE.

BEVILL W. WHITWORTH, OF CEDAR FALLS, IOWA, ASSIGNOR OF ONE-THIRD TO THOMAS A. WHITWORTH AND ONE-THIRD TO CHARLES S. WHITWORTH, BOTH OF CEDAR FALLS, IOWA.

FASTENING MEANS FOR DOORS.

1,262,291.

Specification of Letters Patent.

Patented Apr. 9, 1918.

Application filed October 29, 1917. Serial No. 199,000.

To all whom it may concern:

Be it known that I, BEVILL W. WHITWORTH, a citizen of the United States of America, and a resident of Cedar Falls, 5 Blackhawk county, Iowa, have invented certain new and useful Improvements in Fastening Means for Doors, of which the following is a specification.

My invention relates to improvements in 10 fastening means for doors, and the object of my improvement is to supply simple and convenient means for releasably fastening doors to door casings, and which will be particularly applicable to grain doors for 15 cars, my improved fastening means being adjustable to secure doors of differing widths interchangeably.

This object I have accomplished by the 20 means which are hereinafter described and claimed, and which are illustrated in the accompanying drawings, in which Figure 1 is a front elevation of a door casing and door, with the door secured to the casing by my improved fastening-means; Fig. 2 is a 25 front elevation, on a magnified scale, of said fastening means as connected to a door jamb; Fig. 3 is an end elevation of the same; Figs. 4 and 5 are perspective views of opposite ends of the slide and attached cam 30 of said fastening means, and Fig. 6 is a perspective view of the socketed base bar of the fastening means.

Similar numerals of reference denote corresponding parts throughout the several 35 views.

The numeral 15 denotes the door casing of any structure, such as a freight-car used for carrying grain.

I have shown a door closure for the door 40 opening of said casing composed of sections 16, 17 and 18, the construction of which is described and claimed in another application for patent now pending.

The door or closure which is formed of 45 said sections, or any other type of door, whether single or sectional overlaps and is secured to the jambs of the door casing 15 by means of my improved fastening means. This fastening means is devised to adjustably 50 secure doors of different widths to said jambs, as it often happens that grain doors of different widths are found in different cars, in which the interspace of the door casings are not of coincident dimensions.

55 The numeral 1 denotes a base-bar pro-

vided with a plurality of spaced rectangular sockets in its outer face, the sockets being of like dimensions, and each having a concave inner wall. The door has at opposite ends of its front face like horizontal recesses 11 wider in vertical dimensions than said bar 1, the bar being secured flush therein by means of screw-bolts 13 passed through orifices 3. The bar 1 is trapezoidal in cross-section and upon it is slidably mounted a slide-body 4 whose longitudinal trapezoidal channel or groove 5 fits it upon the bar to prevent its displacement therefrom. The slide-body 4 has oppositely-extending cylindrical pins on its opposite ends, one pin 10 adapted to enter a socket 14 in the door-jamb, the other pin 6 serving as a bearing or support for a cam 8 mounted rotatably thereon, said cam having a handle 9. The cam 8 is of such a form and 75 size as to be received into any of the like sockets 2 in said bar 1 to fit the concavity thereof and to frictionally interlock therewith when the handle 9 is swung downwardly as shown by the full lines in said 80 Fig. 3. When the handle 9 is swung upwardly to the position indicated by the dotted lines in said Fig. 3, it clears said bar 1 permitting the slide-body 4 to be moved longitudinally along the bar in either direction to any position of adjustment therealong. The door is placed to contact with the rear face of the door-casing 15, and the slide-body then moved along the bar 1 to engage the adjacent jamb, as shown in Fig. 90 2, when the cam may be rocked downwardly to secure it in the underlying socket 2, the pin 10 having been received into the socket 14 of the jamb. The cam is secured on the other pin 6 by means of a split-key 7, or by 95 riveting over the extremity of the pin, or in any other convenient manner.

In practice pairs of such fastening means are employed placed on opposite sides of the door to engage the opposite jambs, as shown 100 in Fig. 1, which firmly locks the door in place against either longitudinal movements or movements at a right angle to the door, without any modifications or additions to the door-casing other than the provision of 105 a few sockets 14 in the jambs which do not materially weaken the structure. The fastenings are quickly released by swinging up the cams, and sliding the slide-bodies 4 to remove the pins 10 from the sockets 14. 110

Having described my invention, what I claim as new, and desire to secure by Letters Patent, is:

1. In combination, a door-jamb having a 5 socket, a door having a plurality of like concave alined sockets, a slide-body mounted adjustably and slidably upon said door to move to and from said jamb socket, said slide-body having a pin movable into said 10 jamb-socket, and a convex cam mounted to rock upon said slide-body and receivable fittingly and compressively into any of said door-sockets when the slide-body is adjusted and locked with said jamb by engagement, 15 of its pin with said jamb-socket.
2. In combination, a door-jamb having a socket, a door overlapping said jamb and having a grooved seat, a plate secured in said grooved seat flush with the surface of 20 the door to underlie the jamb, said plate having a plurality of like semi-cylindrical sockets, a slide-body slidably mounted on said plate and having a pin adapted to en-

ter and engage said jamb-socket, and a cam mounted to rock on said slide-body and 25 adapted to be shifted to engage either door-socket to hold the door against longitudinal movements or movements at a right angle to the door.

3. In combination, a door-jamb having a 30 socket, a door having a depressed seat therein underlying said jamb, a plate secured removably in said seat and provided with a plurality of alined like concave sockets, an engaging-device mounted slidingly on said 35 plate and adapted to engage said jamb-socket, and a convex cam rotatable on said engaging-device to engage either of the said door-sockets compressively.

Signed at Lincoln, Nebr., this 22nd day of 40 Oct., 1917.

BEVILL W. WHITWORTH.
